(Continued)

Primary Examiner — Phillip S Hyder(74) *Attorney, Agent, or Firm* — Polsinelli PC(57) **CLAIM**

The ornamental design for a nectar bottle for a bird feeder, as shown and described.

DESCRIPTION

FIG. 1 is a front perspective view of an embodiment of a nectar bottle for a bird feeder embodying my new design.

FIG. 2 is a left side view thereof.

FIG. 3 is a right side view thereof.

FIG. 4 is a top view thereof; and,

FIG. 5 is a bottom view thereof.

*The broken lines depict portions of the nectar bottle for a bird feeder in which the design is embodied that are not considered part of the claimed design.***1 Claim, 5 Drawing Sheets****Matter enclosed in heavy brackets [ ] appears in the original patent but forms no part of this reissue; matter printed in italics indicates the additions made by reissue.**AMENDED
